UNITED STATES PATENT OFFICE.

THEODORE W. FOSTER, OF PROVIDENCE, RHODE ISLAND.

DESIGN FOR A HANDLE FOR BUTTON-HOOKS, &c.

SPECIFICATION forming part of Design No. 31,066, dated June 27, 1899.

Application filed June 2, 1899. Serial No. 719,147. Term of patent 7 years.

To all whom it may concern:

Be it known that I, THEODORE W. FOSTER, of Providence, in the county of Providence and State of Rhode Island, have invented and 5 produced a new and original Design for the Handle of a Button-Hook or Similar Article, of which the following is a specification, reference being had to the accompanying drawings, forming part thereof.

10 Figure 1 is a side view of a button-hook provided with a handle, showing my design. Fig. 2 is a sectional view of the handle on the line X X of Fig. 1.

The leading features of my design consist 15 in the many-sided shaft surmounted with ornaments subdivided by annular beads, forming one end of the handle, and the raised foliated scroll ornament forming the butt-end of the handle.

20 In the drawings, *a* indicates the shaft of the handle, formed of ten flat sides or facets *a' a'* of uniform width; *b*, a beaded ring inclosing the end of the shaft *a*; *c*, a scroll ornament inclosing a small panel; *d*, a shell ornament 25 extending from the scrolls to the annular

beads *e*, having a concavo-convex vertical outline. The flame-covered bulb *f* extends from the beads *e* to the two superimposed annular beads *g*, forming the ferrule of the handle. *h* is the button-hook. The blade of a paper-cutter (indicated in broken lines) may replace the button-hook. The butt ornament consists of two raised and foliated scrolls *i*, extending from a foliated center and inclosing the elongated panel *j*. The foliated scrolls *i* are surrounded by the floral ornament *k*, the butt ornament presenting when viewed from the side an approximately oval outline. 30 35

Having thus described my invention, what I claim as new, and desire to secure by Letters 40 Patent, is—

The design for the handle of a button-hook or similar article herein shown and described.

In witness whereof I have hereunto set my hand.

THEODORE W. FOSTER.
